(57) **CLAIM**

The ornamental design for a scoop-front garment, as shown and described.

DESCRIPTION

FIG. 1 is a front elevation view of a scoop-front garment. FIG. 2 is a right-side perspective view of the scoop-front garment.

FIG. 3 is a rear elevation view of the scoop-front garment with the rear portion of the shoulder straps in a wide position.

FIG. 4 is a left-side (wearer's right side) elevation view of the scoop-front garment; the right side elevation view is an identical mirror image thereof.

FIG. 5 is a top elevation view of the scoop-front garment. FIG. 6 is a bottom elevation view of the scoop-front garment; and,

FIG. 7 is a front elevation view of FIG. 3 shown in a first alternate configuration with the rear portion of the shoulder straps in a narrow position.

The broken lines indicate portions of the article not claimed and form no part of the claimed design. The broken lines in the drawings shown within the cup panels of the article represent unclaimed seams and form no part of the claimed design.
